ATTORNEY IN FACT

UNITED STATES PATENT OFFICE.

JOHN M. BARR, OF PITTSBURG, PENNSYLVANIA, ASSIGNOR TO WESTINGHOUSE ELECTRIC & MANUFACTURING COMPANY, A CORPORATION OF PENNSYLVANIA.

DYNAMO-ELECTRIC MACHINE.

No. 888,456.

Specification of Letters Patent.

Patented May 26, 1908.

Application filed October 5, 1907. Serial No. 396,044.

To all whom it may concern:

Be it known that I, JOHN M. BARR, a citizen of the United States, and a resident of Pittsburg, in the county of Allegheny and State of Pennsylvania, have invented a new and useful Improvement in Dynamo-Electric Machines, of which the following is a specification.

My invention relates to electrical apparatus, and has special reference to magnetizable core members which are provided with coil-containing slots.

The object of my invention is to provide a simple and durable means for effectually holding the coils of open slot machines in position, against the action of centrifugal, magnetic and other forces tending to displace them and at the same time to provide the operating advantages which pertain to machines having partially closed slots.

Induction motors and other dynamo-electric machines are often utilized in rolling mills and other places where continuous operation is desired and where material loss would result if considerable time was required for repairing their windings. In such cases, it is especially desirable that the core slots be of the open type having substantially parallel side walls, so that injured coils may be replaced without difficulty.

According to my present invention, I provide means for holding the coils of open slot machines in position and at the same time securing the well known advantages incident to the use of partially closed slots.

Figure 1, of the accompanying drawings, is a partially sectional elevation of a portion of a dynamo-electric machine member provided with one of my coil-retaining devices and Fig. 2 is a similar view showing a modification of my invention.

Referring to Fig. 1, of the drawings, the structure illustrated comprises a magnetizable core 1 having a plurality of teeth 2 which form slots 3 to receive coils 4 and are provided with grooves 5 in their sides and near their free ends. The coils 4 are held in position by wedges 8 each of which comprises side pieces 9 and 10 of insulating material having lateral projections or beads 11 and 12 which are adapted to engage the grooves 5 in adjacent teeth of the core structure. The pieces 9 and 10 are spaced apart by a resilient magnetizable strip 13 which engages slots 14 and 15 therein and is bowed

inwardly from edge to edge. When the dynamo-electric machine is in operation the magnetizable strips 13 will be subjected to considerable magnetic influences tending to displace them, and, if the wedges are embodied in the rotating member, centrifugal forces will also tend to displace them and the coils. These forces are not only resisted by wedges constructed in accordance with my invention but any force which tends to move them nearer the mouths of the core slots also tends to bend the strips 13 outwardly and thus press the insulating pieces 9 and 10 more firmly into the grooves 5.

Referring now to Fig. 2, of the drawing, the core parts are the same as in Fig. 1 and the wedges 16 may have the same form as the wedges 8 but, in this modification, the side pieces 17 and 18 are, either wholly or partially, of magnetizable material and are separated from the adjacent portions of the core by insulating material 19. In this structure, the intermediate resilient strip 20 is composed of non-magnetic material such, for example, as bronze and is insulated from the side pieces 17 and 18 by suitable non-conducting material.

It will be observed that both forms of my invention constitute reliable coil-retaining means and also provide the operating conditions incident to partially closed slots without relinquishing the construction and repair advantages which pertain to open slot machines.

My improved wedge structure is, of course, not limited in its application to any specific class of electrical apparatus, and I desire that only such limitations shall be imposed as are indicated in the appended claims.

I claim as my invention:

1. In a dynamo-electric machine, the combination with a magnetizable core member having a plurality of coil-containing slots, of wedges for holding the coils in position each of which comprises insulating side pieces and a resilient magnetizable spacer between said pieces.

2. In a dynamo-electric machine, the combination with a magnetizable core member having a plurality of coil-containing slots and longitudinal grooves near the mouths of the slots, of wedges for holding the coils in position each of which comprises beaded pieces of insulating material that engage the grooves and a resilient bowed spacing strip.

of magnetizable material which tends to force the insulating pieces into the grooves.

3. In a dynamo-electric machine, the combination with a magnetizable core member having teeth which form slots for the reception of coils and are provided with grooves in their sides and adjacent to their free ends, of wedges for holding the coils in position in the slots each of which comprises pieces of insulating material having lateral projections or beads that fit into the groove and a resilient bowed spacing strip of magnetizable material which tends, under the influence of external forces, to force the pieces into the grooves.

4. In a dynamo-electric machine, a core having coil-containing slots and coil-retaining wedges each of which comprises two side pieces and an inwardly curved intermediate strip, at least one of said wedge parts being magnetizable.

5. In a dynamo-electric machine, a core

having coil-containing slots provided with grooves in their side walls and coil-retaining wedges each of which comprises side pieces 25 to engage said grooves and an intermediate resilient strip of inwardly curving contour, at least one, but not all of said wedge parts being magnetizable.

6. In a dynamo-electric machine, a core 30 having coil-retaining slots provided with grooves in their side walls and coil-retaining wedges each of which comprises side pieces to engage said grooves and a resilient, inwardly curved strip, at least one of said 35 wedge parts being magnetizable.

In testimony whereof, I have hereunto subscribed my name this 30th day of Sept., 1907.

JOHN M. BARR.
